UNITED STATES PATENT OFFICE

EARL BLACKER, OF EVERETT, WASHINGTON

BAG-DELIVERING MACHINE

Application filed May 7, 1929. Serial No. 361,125.

The object of my invention is to provide a novel and efficient bag delivering machine whereby one bag at a time may be conveniently removed from the pack of bags held by the machine and whereby bags of different sizes are conveniently arranged for withdrawal from the apparatus; and to provide the novel combination and arrangement of parts hereinafter described.

10 I attain these and other objects of my invention by the mechanism illustrated in the accompanying drawings, in which,—

Figure 1 is a front elevation of the entire apparatus;

15 Fig. 2 is a side elevation of same;

Fig. 3 is a horizontal section on line 3—3 of Fig. 2, the main portion of the apparatus being shown in top plan;

20 Fig. 4 is a perspective view of the machine showing a person in the act of starting to remove a bag from the bag casing; and

Fig. 5 is a similar view showing the bag nearly withdrawn from the bag casing.

Like numerals designate like parts in each 25 of the several views.

Referring to the accompanying drawings, I provide a rack 1 having hooks 2 which engage the arm 4 affixed to the bag casing 3. I provide a weight member 7 mounted on the 30 ends of arms 8 which are provided with pivots 9 pivotally mounted in the arm 4. The casing 3 is provided with a roller 5 near the top thereof, the roller being mounted on suitable pivots 6, as shown in the drawings. The 35 weight member 7 has an arm or wire 10 affixed at 12 to the weight member and terminating in a downturned end 11 adapted to engage the open end of the bags before they are successively withdrawn from the casing 3.

40 I provide two depressions 14 on each side of the upper portion of the casing 3 to cause friction on the sides of the bags and help hold the bags in place, except the outer bag.

45 In use the upper portion of the upper bag is grasped by the hand, as shown in Fig. 4, and then withdrawn, as shown in Fig. 5, the bag opening as it is withdrawn and allowing the next bag of the pack to come to the front as the outermost bag is pulled outward and downward through the depressions

14 over the freely rotatable roller 5. The machine thus allows positive delivery of one bag at a time and by providing the rack 2 a series of bags of different sizes may be carried in a convenient location for use. The pivoted 55 weight member 7 presses on the rear portion of the pack of bags to hold them in operative position against the roller 5, the hook or wire 10 also engaging the upper portion of the bags to hold same in the desired position as shown 60 in the drawings, whereby to permit the operator to readily grasp the outermost bag and withdraw it.

What I claim is:

1. In a bag delivering machine, the combination of a rack having a series of spaced hooks for engaging bag holding casings, a plurality of such bag holders, said bag holders being of different sizes, each of said bag holders comprising a casing to receive the bags, a U-shaped arm affixed to the casing and adapted to be engaged by one of said hooks on the aforesaid rack, a freely rotatable roller mounted in the upper portion of the casing of the bag holder, a weight element pivotally mounted on the aforesaid U-shaped arm, said weight member also having a wire hook element extending forwardly and loosely engaging the outermost bag, whereby to automatically open the outermost bag to facilitate 75 its withdrawal by the operator.

2. In a bag delivering machine, the combination of a box-like metal bag holder open at one end, said holder having an arm affixed to it and extending beyond it for attaching the holder to a suitable support, a loosely mounted roller carried in the upper portion of the holder, a weight element pivotally mounted on the rear portion of the holder, 80 said weight member also having a wire hook element extending forwardly and having its downturned end loosely engaging the outermost bag, whereby to automatically open the bag to facilitate its withdrawal by the operator.

3. In a bag delivering machine, the combination of a box-like metal bag holder open at one end, said holder having an arm affixed to it and extending beyond it for attaching the holder to a suitable support, a loosely 85

- mounted roller carried in the upper portion of the holder, a weight element pivotally mounted on the rear portion of the holder, said weight member also having an L-shaped wire hook element extending forwardly and having its downturned end loosely engaging the outermost bag, whereby to automatically open the bag to facilitate its withdrawal by the operator.
4. In a bag delivering machine, the combination of a box-like bag holder open at one end, said holder having an arm affixed to it and extending beyond it for attaching the holder to a suitable support, a loosely mounted roller carried in the upper portion of the holder, a weight element bearing on the bags directly over the roller, said weight member also having a wire hook element extending forwardly and having its downturned end loosely engaging the outermost bag, whereby to automatically open the bag to facilitate its withdrawal by the operator.
5. In a bag delivering machine, the combination of a box-like bag holder open at one end, said holder having an arm affixed to it and extending beyond it for attaching the holder to a suitable support, a loosely mounted roller carried in the upper portion of the holder, a weight element bearing on the bags directly over the roller, said weight member also having a wire hook element extending forwardly and having its downturned end loosely engaging the outermost bag, whereby to automatically open the bag to facilitate its withdrawal by the operator, the bag holder having opposite depressions in its upper portion to frictionally engage the sides of the bag and help hold it in place.
6. In a bag delivering machine, the combination of a rack having a series of spaced hooks for engaging bag holding casings, a plurality of such bag holders, said bag holders being of different sizes, each of said bag holders comprising a casing to receive the bags, a U-shaped arm affixed to the casing and adapted to be engaged by one of said hooks on the aforesaid rack, a freely rotatable roller mounted in the upper portion of the casing of the bag holder, a weight element pivotally mounted on the aforesaid U-shaped arm, said weight member also having a wire hook element extending forwardly and loosely engaging the outermost bag.

EARL BLACKER.
